UNITED STATES PATENT OFFICE.

WILLIAM C. KITCHELL, OF ORMOND, FLORIDA.

ROLLER-TIMER.

1,086,598.

Specification of Letters Patent. Patented Feb. 10, 1914.

Application filed March 3, 1913. Serial No. 751,779.

To all whom it may concern:

Be it known that I, WILLIAM C. KITCHELL, a citizen of the United States, residing at Ormond, in the county of Volusia, State of Florida, have invented certain new and useful Improvements in Roller-Timers; and I do hereby declare the following to be a full, clear, and exact description of the invention, such as will enable others skilled in the art 10 to which it appertains to make and use the same.

This invention relates to gas engine timers and has for an object to provide an extremely simple timer having a novel spring pressed 15 roller contact with the rotary contact carried by the engine shaft.

With the above object in view the invention consists of certain novel details of construction and combination of parts herein- 20 after fully described and claimed, it being understood that various modifications may be made in the minor details of construction within the scope of the appended claims.

In the accompanying drawing illustrating 25 this invention: Figure 1 is a side elevation of the device applied. Fig. 2 is a longitudinal sectional view through the device. Fig. 3 is a front elevation with parts in section. Fig. 4 is a cross section on line 4—4 30 Fig. 1. Fig. 5 is a front elevation of a modified form of the invention. Fig. 6 is a longitudinal sectional view through the modified form.

Referring now to the drawing in which 35 like characters of reference designate similar parts, 10 designates a lever which is adapted to be clamped in upright position to the engine crank shaft bearing 11 by means of a split ring clamp 12, the lever being 40 equipped on one side with an arm 13 which is provided with an opening 14 in which is mounted a nipple nut 15 formed of insulating material.

A sleeve 16 formed of metal has the lower 45 end threaded and passed through the nipple nut 15, a nut 17 being threaded on to the sleeve and bearing against the flange of the nipple nut, and a second nut 18 being threaded on to the sleeve and bearing against a 50 washer 19 of insulating material that bears upon the bottom face of the arm 13 and nipple nut, the sleeve being thus securely clamped to the arm by the nuts 17 and 18 and being insulated therefrom by the nipple 55 nut 15 and washer 19. The sleeve is pro-

vided with a longitudinal slot 20 near the top.

A shaft 21 is slidably fitted in the sleeve and is held against rotation therein by means of a pin 22 that is integral with the 60 shaft and projects into the slot 20 of the sleeve. The shaft projects below the sleeve and is terminally equipped with a fork 23 that carries a shaft 24 upon which a roller 25 is journaled, all of these parts being of 65 metal. The shaft is equipped at the top with a binding post 26 by means of which the ground wire from the coil or battery may be secured to the shaft. A helical spring 26' is seated on the shaft and is con- 70 fined under tension between the nut 18 and fork of the shaft, this spring exerting a downward pressure upon the fork and holding the roller in snug engagement with the rotary contact carried by the engine crank 75 shaft.

Snugly surrounding the engine crank shaft 27 in vertical alinement with the roller is a rotary contact comprising a pair of insulating rings 28 between which is clamped 80 a metal ring 29 that has a radial contact 30 which extends to and is exposed upon the peripheries of the insulating rings. A circular series of bolts 31 is passed through all of these rings and into the engine fly-wheel 85 32 to rigidly secure the disks to the fly-wheel.

In operation it will be seen that the ignition circuit is closed when the roller 25 comes in contact with the rotating contact 90 30, and further that by shifting the lever 10 to the right or left the time of such contact is changed with respect to the crank shaft whereby the time of ignition is advanced or delayed. 95

In Fig. 5 is shown a modified form of the invention, in which the engine shaft is designated by the numeral 33. The timer in this instance is secured to the extreme end 100 of the shaft and to attain this end I provide a sleeve 34 which is secured to the shaft by a set screw 35 or otherwise and is formed with an axial cylindrical extension 36 which forms a prolongation of the shaft 33, the extension being circumferentially reduced to 105 provide an axial stem 37 which is terminally threaded to receive a nut 38. A fiber casing 39 is secured to the extension 36 for rotary movement thereon, and to attain this end a disk 40 is secured to the rear face of the cas- 110

ing by means of screws 41 or otherwise, the disk having an integral nipple 42 which surrounds the extension 36, and further having an operating lever 43 which is normally held stationary in any preferred manner and may be shifted to rotate the casing on the extension and thus advance or retard the spark, as will presently appear. A metal disk 44 is secured between a pair of insulating disks 45, and the latter clamped upon the metal disk by means of the above mentioned nut 38 which binds the disks 44 and 45 snugly together against the shoulder 46 of the extension 36, the disk 44 being provided with an extension 47 that extends to the periphery of the insulating disks 45. A metal sleeve 48 is threaded at one end through an opening 49 in the circular wall of the casing 39 and is clamped to the latter by means of nuts 50 and 51 threaded on to the sleeve against the inner and outer faces respectively of said circular wall. A cylindrical stem 52 is slidably fitted in the sleeve and projects beyond both ends of the sleeve, the outer ends of the stem being fitted with a binding post 53 to receive an ignition wire. The inner end of the stem is equipped with a fork 54 in which is revolvably mounted a roller 55 which is formed of metal and rides upon the peripheries of the insulating disks and extension 47 of the metal disk 44. A helical spring 56 is seated on the stem within the sleeve 48 and urges the roller into tight contact with the disks above described, one end of the spring bearing against a nipple nut 57 which is threaded in the outer end of the sleeve and is locked in adjusted position by a set nut 58. But one roller and attaching means therefor is shown, so that a single spark will be produced at each revolution of the projection 47 under the roller. It is to be understood that as many rollers may be employed as will be required to produce any desired number of sparks at each revolution of the disk 44 in order to adapt the device to multi-cyl-

inder engines. Secured within the casing 39 opposite from the spring pressed roller 55 is an abutment block 59 the inner edge of which bears upon the peripheries of the disks 45 and holds the latter against dislodgment due to the pressure of the roller 55. In case a plurality of rollers are used, there is no necessity for the use of abutment blocks as above described, since the rollers 55 counteract the effect of each other as will be understood.

What is claimed, is:—

1. In a timer, a supporting lever having a laterally projecting arm provided with an orifice, a tubular insulating element in said orifice having terminal flanges fitting against opposite faces of said arm, a sleeve in said element and having a threaded end projecting therethrough, set nuts threaded on said sleeve and bearing against respective flanges of said element and adjustably securing said sleeve to said arm, a spring pressed shaft slidably and non-rotatably fitted in said sleeve, and a contact roller carried by said shaft.

2. The combination with an engine shaft, of a sleeve fixed to the end of said shaft and having an axial cylindrical extension, said extension terminating in a reduced axial terminally threaded stem, a casing formed of insulating material loosely mounted upon said extension and adapted to normally be held stationary thereon, a metal disk on said stem having a radial extension, insulating disks on opposite sides of said metal disk having the peripheries extending flush with the outer edge of said radial extension, and a spring pressed contact roller carried by said casing and riding upon the peripheries of said insulating disks and said extension.

In testimony whereof, I affix my signature, in the presence of two witnesses.

WILLIAM C. KITCHELL.
